UNITED STATES PATENT OFFICE.

HENRY JAMIESON, OF GILLESPIE, ILLINOIS.

SWITCH APPARATUS.

1,244,738.

Specification of Letters Patent.

Patented Oct. 30, 1917.

Application filed August 25, 1916. Serial No. 116,891.

To all whom it may concern:

Be it known that I, HENRY JAMIESON, a citizen of the United States, residing at Gillespie, in the county of Macoupin and State of Illinois, have invented certain new and useful Improvements in Switch Apparatus, of which the following is a specification.

My invention relates to improvements in automatically operated switch apparatus, wherein a trip member is employed for throwing the switch points.

An important object of the invention is to provide a switch of the above mentioned character, which is automatic and reliable in operation, and not liable to derangements.

A further object of the invention is to provide means to derail the cars if they run back from the side track on to the main track, while the switch points are operative with respect to the main track.

Other objects and advantages of the invention will be apparent during the course of the following description.

In the accompanying drawings forming a part of this specification and in which like numerals are employed to designate like parts throughout the same,

Figure 1 is a plan view of a switch embodying the invention,

Fig. 2 is a side elevation of the same,

Fig. 3 is a longitudinal sectional view taken on line 3—3 of Fig. 1,

Fig. 4 is a transverse sectional view taken on line 4—4 of Fig. 2,

Fig. 5 is a similar view taken on line 5—5 of Fig. 2, and,

Fig. 6 is a similar view taken on line 6—6 of Fig. 2.

In the drawings, wherein for the purpose of illustration is shown a preferred embodiment of my invention, the numeral 5 designates the main track rails, and the numeral 6 designates the side track rails. The numeral 7 designates the usual frog.

Pivotedly connected with one section of the track rail 5 is a switch point 8, and a co-acting point 9 is pivotedly connected with one rail section 6, as shown. These switch points are pivotedly connected with a transverse reciprocatory bar 10, as shown in 11. This bar passes beneath one rail 5 and its free end is pivotedly connected with a horizontally swinging lever 12, as shown at 13. This horizontally swinging lever projects into a stationary housing 14, secured to the

base 15. The lever 12 is pivoted within the housing 14. The base 15 is provided with longitudinally extending guides or flanges 17, within which is mounted a reciprocatory slide 18, and actuating rollers 19 and 20 are disposed upon opposite sides of the lever 12 and are pivotally connected with the slide 18, by means of stub-shafts 21. These stub-shafts are also attached to an upper plate or member 22, which is accordingly secured to the slide 18.

The slide 18 and its upper plate 22 are connected with a reciprocatory bar or rod 23, which serves to operate it. The bar 23 operates within a stationary guide 24, and is provided near this guide with a longitudinal slot 25, as shown.

Arranged adjacent the end of the bar 23 and extending through the slot 25 thereof is a normally vertical trip 26, comprising spaced arms 27, which are rigidly secured together. The trip 26 is pivotally supported near its lower end, as shown at 29, and this lower end carries a counterweight 30. This counterweight 30 serves to normally retain the trip in the vertical position and to return it to the vertical position when removed therefrom. The trip 26 extends outwardly beyond the track rails for a substantial distance and is adapted to contact with a projection on the frame of the engine or motor, and be swung thereby. Connected with opposite end of the plate 22, preferably at the stub-shaft 21, is a bar or rod 31, having a longitudinal opening 32, receiving the normally vertical trip 33, preferably identical with the trip 26, and therefore need not be described again in detail. The trip 33 is pivoted at 34, and its lower end is counterweighted, as shown.

Arranged forwardly of an adjacent the cross-rail 6 is a pivoted derailed 35, having pivotal connection with a pitman 36. This pitman 36 is pivotally connected with a horizontally swinging bell-crank lever 37, pivoted to the bar 23, as shown at 37'. When the switch points 8 and 9 are swung to closed position, the derailed 35 is moved into proximity to the rail 6, thus preventing the return of cars from the side track on to the main track.

In operation, the engines or motors which are intended to travel down the main track, in the direction of its arrows, are equipped with a suitable projection to contact with the trips 26 and 33. Assuming that the

switch points 8 and 9 are set so that the engine or motor would pass upon the side track, the trip 33 will be in a vertical position and when the projection on the motor contacts therewith, such trip will be swung in the direction of its arrow. This swinging movement of the trip 33 will move the bar 31 to the left, and the slide 18 will move to the left. The co-acting rollers 19 and 20 will then swing the lever 12 inwardly toward the track 5 and the bar 10 will shift the rail points 8 and 9 so that the engine or motor will travel down the main track. When the projection on the engine or motor contacts with the trip 26, such trip is swung to the right in the direction of its arrow and the bar is shifted to the right. This movement of the bar 23 moves the slide 18 to the right and the lever 12 is shifted outwardly. The bar 10 is shifted outwardly and the rail points 8 and 9 returned to the position so that the next engine or motor which is not equipped with the projection will travel on to the side track. It is obvious that the opposite of this operation occurs when the motor equipped with the projection travels in an opposite direction along the main track, and upon passing over the switch.

30 It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

40 1. In apparatus of the character described, the combination with pivoted switch points of a railway switch, of a reciprocatory slide having spaced members carried thereby, a pivoted lever arranged between the spaced members to contact therewith and be moved thereby, means connecting the pivoted lever with the switch points, and a trip member connected with the slide to move it.

Copies of this patent may be obtained for five cents each, by addressing the "Commissioner of Patents, Washington, D.C."

2. In apparatus of the character described, the combination with pivoted switch points of a railway switch, of a reciprocatory slide having spaced members carried thereby, a pivoted lever arranged between the spaced members to contact therewith and be moved thereby, means connecting the pivoted lever with the switch points, a trip member connected with the slide to move it, and means to return the trip member to the normal position. 50

3. In apparatus of the character described, the combination with pivoted switch points of a railway switch, of a reciprocatory slide, spaced rollers pivotally mounted upon the slide, a pivoted lever arranged between the rollers to contact therewith and be moved thereby, a bar pivotally connected with the switch points and with the pivoted lever, a pivoted trip member, a rod connected with the slide and having a longitudinal slot to receive a portion of the trip member, and means to move the trip member to a normal vertical position. 60

4. In apparatus of the character described, the combination with a movable switch point, of a swinging lever pivoted at one end and connected with the switch point at the other end, a plurality of elements arranged upon opposite sides of the swinging lever to contact therewith and shift the same laterally, and means to move the plurality of elements. 75

5. In apparatus of the character described, the combination with a movable switch point, of a swinging angularly arranged member connected therewith to move the same, elements arranged upon opposite sides of the swinging member to contact therewith and move the same laterally, and means to move the elements longitudinally 90 of the swinging member. 85

In testimony whereof I affix my signature in presence of two witnesses.

HENRY JAMIESON.
